[57] **CLAIM**

The ornamental design for a telephone base, as shown and described.

DESCRIPTION

FIG. 1 is a front, top and right side perspective view from above showing my new design;

FIG. 2 is a left side elevational view thereof; and

FIG. 3 is a rear elevational view thereof.

The bottom of the base is plain and unadorned.

Fig. 1.

*Fig. 2.**Fig. 3.*
